UNITED STATES PATENT OFFICE.

PETER DUBOIS, OF CHICAGO, ILLINOIS, ASSIGNOR TO PETRICK BROTHERS, OF CHICAGO, ILLINOIS, A PARTNERSHIP COMPOSED OF FRANK PETRICK AND EDWARD PETRICK.

CHART HOLDER.

Application filed February 7, 1921. Serial No. 442,944.

To all whom it may concern:

Be it known that I, PETER DUBOIS, a citizen of Holland, residing at Chicago, in the county of Cook and State of Illinois, have 5 invented certain new and useful Improvements in Chart Holders, of which the following is a specification.

My invention relates to chart holders and consists in a casing, and clips adapted to 10 be inserted therein to hold charts, maps, samples of paper, cloth or other thin sheets whether flexible or rigid.

The main object of my invention is to provide a simple, economical holder which 15 is adapted to suspend charts, etc., and to permit substitution, and variations in the number of charts.

Such a holder must be large enough to accommodate a predetermined, maximum 20 number of sheets and another object of my invention is to provide means for suspending a lesser number of sheets as securely and in the same position as if the holder was full.

25 In the accompanying drawings illustrating my invention

Fig. 1 is a rear elevation of my holder showing some sheets suspended and part of a supporting stand.

30 Fig. 2 is a vertical, transverse section on the line 2—2 of Fig. 1.

Fig. 3 is a rear elevation of one of the clips.

Fig. 4 is a vertical, transverse section on 35 the line 4—4 of Fig. 1 and

Figs. 5 and 6 are respectively rear and side elevations of a modified form of clip.

The holder casing 1 is formed substantially from a single plate bent to the form 40 shown in Fig. 2 which comprises vertical spaced walls 2 and 3 united by the top 4. The lower end of front wall 2 is bent upwardly at 5 to form a groove 6. The upper portion of the rear wall 3 is bent outwardly to form a recess 7 which provides 45 wall 3 with an upwardly facing ledge 8.

The ends of the casing comprise sheet metal stampings 9 and 10, each in the form of a shallow cap having the outline of a 50 cross section through the casing. These may be screwed or riveted to the casing as indicated at the left hand of Fig. 1. Preferably one of them, at least, is removably secured to the casing by tongue 55 and slot means as indicated at the right hand

of Fig. 1 and detailed in Fig. 4. With this latter construction, the walls 2 and 3 are provided with outwardly projecting tongues preferably stamped therefrom which are adapted to enter corresponding recesses 60 formed in the cap 10 to hold the latter in place. By springing the walls 2 and 3 slightly inward the tongues are withdrawn from the recesses permitting the cap 10 to be slipped from the end of the casing. 65

Each clip 12 preferably consists of a one piece element bent so as to have substantially the same shape as casing 1 but somewhat smaller and without the upturned flange 5 of the latter. The clip is formed 70 of flexible material and has an integral tongue 13 stamped from one leg 14 thereof. The opposite leg 15 is provided with a slot through which tongue 13 may be passed.

Fig. 2 shows casing 1 and clip 12 assembled. The full line position of clip 12 indicates its shape and location when comparatively few sheets are mounted in the holder and the dotted line position represents it when the holder is filled to maximum capacity. 75

It will be noted that the lower edge of front leg 15 of the clip is supported and retained in the groove 6 of the casing and that the shoulder on the rear of the clip is 85 supported on the ledge 8 of the casing. This is true whether the clip legs are close together or far apart as the rearwardly extending portion of the clip always remains within the casing recess 7 and rests upon the 90 casing ledge 8. The flange 5 on the front casing wall retains the front leg 15 of the clip and consequently the suspended sheets are always adjacent the front of the casing.

Intermediate the ends of casing 1 on its 95 rear side is a bracket 16 adapted to receive the upper end of a rod 17 which forms part of a pedestal for supporting the chart holder. If necessary, the casing may be reinforced at this point by a stiffening plate 100 18.

While, as mentioned above, the casing walls 2 and 3 may be sprung sufficiently to release tongues 11 from the slots in the end caps, it is to be understood that the casing 105 is substantially rigid so that it retains its shape irrespective of the load which it may support.

In the clip illustrated in Figs. 5 and 6, a bolt 19 is substituted for the clip tongue. 110

Where frequent insertions or removals of sheets are required this construction will be advantageous as repeated bending of tongue 13 would result in fracture of the tongue.

5 The sheets to be mounted in the holder are first gripped by two or more of the clips spaced from each other and the clips with the upper ends of the sheets are slid into the casing endwise and the removable 10 cap positioned on the casing. When it is desired to replace one of the sheets or insert an additional sheet the cap is removed and the clips and sheets are withdrawn through the open end of the casing, the clips 15 opened, the new sheet placed in position and the clips reassembled and the sheets and clips reinserted in the casing.

It will be apparent that various changes 20 may be made in the form, construction and arrangement of the parts without departing from the spirit and scope of my invention or sacrificing any of the material advantages thereof and I reserve the right to make all such changes as fairly fall within the scope 25 of the following claims.

I claim:

1. In a chart holder, a casing having a longitudinal groove and a longitudinal ledge, and a chart clip supported by said 30 casing, and having a leg to rest in said groove, and a shoulder to lie on said ledge.

2. In a chart holder, a casing and a chart clip, said clip having a downwardly extending leg and a rearwardly extending 35 shoulder, and said casing having an upwardly facing groove to support the end of said leg, and a ledge to support said shoulder.

3. In a chart holder, a casing and an adjustable chart clip, said clip having a downwardly extending leg and a rearwardly extending shoulder; and said casing having an upwardly facing groove to support the edge 45 of said leg, and a ledge adapted to support said shoulder irrespective of the adjustment of said clip.

4. In a chart holder, a casing comprising

a plate bent to provide spaced, vertical walls, one wall being provided with an upwardly facing groove at its lower edge and the other wall being provided with an inner recess adjacent its upper edge, and a chart clip comprising a strip bent to provide spaced legs, one leg having its lower edge supported in said groove and the other leg being provided with an external shoulder seated on said recess.

5. In a chart holder, a casing having an open bottom, and an open end, a chart clip adapted to be inserted in said casing through said end and to be supported by 60 said casing and a cap removably secured to the open end of said casing.

6. In a chart holder, a rigid casing having an open bottom, and a flexible chart clip adapted to be inserted through an end 65 of said casing and means for supporting said clip within said casing.

7. In a chart holder, a longitudinal casing and a clip adapted to grip one or more 70 chart sheets, said casing being adapted to receive through its end the upper edges of one or more chart sheets and to receive through its end and to support said clip.

8. In a chart holder, a flexible clip 75 adapted to securely grip one or more chart sheets and a casing having an open bottom and adapted to hold said clip in a predetermined position irrespective of the number of sheets it may grip.

9. In a chart holder, a casing having spaced walls and an opening between the lower portion of said walls, a clip having spaced legs and chart suspending means between said legs, said casing walls being provided with clip supporting means.

10. In a chart holder, a casing having a longitudinal groove and a longitudinal ledge, and a plurality of clips adapted to 90 suspend chart sheets and to slide along said groove and ledge and to be spaced from each other lengthwise of the casing by the suspended chart sheets.

PETER DUBOIS.
